ATTACHMENT FOR INTERNAL COMBUSTION ENGINES

George H. Meiser, Chicago, Ill.

Application July 18, 1938, Serial No. 219,889

5 Claims. (Cl. 277—60)

My invention relates to improvements in attachments for internal combustion engines and, more particularly, an air pump adapted for use in connection with a multi-cylinder internal combustion engine, my attachment being primarily adapted for use in connection with motor vehicles for tire inflation, though as will be understood it may be put to other uses.

Devices of this character require for their use merely the removal of a spark plug from one of the cylinders of the engine and the insertion of the device into the spark-plug-receiving opening. The engine is then operated with the remaining cylinders and the one having the device attached operates in conjunction therewith to pump air, the air to be pumped being drawn into the device on the suction stroke of the engine and then compressed on the compression stroke.

As will be understood, it is essential for pumping of high pressures that the means controlling the flow of air from the atmosphere into the device on the engine suction stroke and the shutting off of this air from the atmosphere on the engine compression stroke be as nearly instantaneously reactive to the engine suction and pressure as possible; in other words, that valve-lag be minimized to as great a degree as possible not only because such lag reduces the efficiency of the pump but because unless practically nonexistent on the suction stroke is apt to result in the pumping of gasoline vapor instead of pure air. By providing against valve lag on the suction stroke thus permitting instantaneous flow of air to the pumping cylinder, and providing for the free flow of sufficient quantities of air through the device, suction produced by the pumping cylinder of the engine may be relieved sufficiently to insure against the drawing of gasoline vapor into the cylinder from the intake of the engine in which vacuum exists.

Furthermore, in the use of the device in the spark-plug-receiving opening of the pumping cylinder the inlet for the air drawn into the pumping cylinder through the device is limited to the size of this opening which is relatively small, and it is therefore necessary, in order that the pumping cylinder pump high pressures without pumping gasoline vapor, that the device permit of unrestricted flow of air to the pumping cylinder and that the air inlet valve of the device act without substantial lag in both opening and closing. Restricted flow of air into the device reduces efficiency by reducing the pressure which may be developed and results in the creation of such vacuum in the pumping cylinder,

on its suction stroke, as to draw gasoline vapor from the intake of the engine into the pumping cylinder. Valve lag in the drawing of air into the device not only reduces the pressure which may be developed, but also is apt to result in the pumping of gasoline vapors and valve lag on the compression stroke of the pumping cylinder reduces the pressure developed.

Devices of this character for universal application must be adapted for satisfactory operation on engines which operate not only at low, but relatively high, idling speeds. The higher the idling speed of the engine the more necessary the avoidance of valve lag and avoidance of restricted air flow to the air inlet (spark-plug-receiving opening) of the pumping cylinder, for pumping high pressures without the pumping of gasoline vapors.

Certain of my objects are to provide a device of the character described which will operate to insure such free instantaneous flow of air into the pumping cylinder as to avoid the pumping of gasoline vapor even at relatively high engine-idling speeds; to effect quick shut-off of the device to the atmosphere upon the conclusion of the suction stroke; to provide a device by which high pressures will be produced at any usual engine-idling speeds without pumping gasoline vapors; and to accomplish these results by a novel, simple and inexpensive construction of device.

Another requirement of a device of the character stated is that it shall be adapted for application to use on engines as at present commonly constructed many of which are of such design as to present obstruction to the application thereof of such devices unless provided of relatively small size; it being another of my objects to provide a device by which the purposes above mentioned may be accomplished and yet will be of such small size as to adapt it to be used on engines of such designs that devices of relatively large size cannot be used.

Referring to the accompanying drawing:

Figure 1 is a view in vertical sectional elevation of one of the cylinders of a multi-cylinder internal combustion engine showing it as equipped with a device embodying my invention.

Figure 2 is an enlarged view in vertical sectional elevation of the device of Fig. 1.

Figure 3 is a plan view of the device, the check-valve-equipped cap thereof being removed.

Figure 4 is a plan sectional view taken at the line 4 on Fig. 2 and viewed in the direction of the arrow showing the flap valves forming a part of

the device in the position they assume when air is being drawn into the device.

Figure 5 is a view like Fig. 4 showing the position assumed by the flap valves when air is being 5 expelled from the device.

Figure 6 is a view in side elevation of the flap valves and the cage or retainer therefor showing one of the valves in section; and

Figure 7, a view in side elevation of the cage, 10 the cage being viewed from the right-hand side of Fig. 6.

The illustrated device comprises a cylindrical casing 8 having its lower end somewhat reduced in diameter and provided with external screw 15 threads 9 adapted to be screwed into the spark-plug-receiving opening 10 of one of the cylinders of a multi-cylinder internal combustion engine such as the cylinder 11 of the engine represented at 12.

20 The casing 8 contains diametrically opposed series 13 and 14 of circumferential slots each shown of a length slightly greater than one-fourth of the circumference of the casing, these slots forming air inlets for the purpose herein- 25 after explained.

The air inlets 13 and 14 are controlled by check valves in the form of flap valves 15 and 16, these valves being preferably made of a rubberlike material having the necessary qualities to meet 30 the conditions of use in connection with an internal combustion engine, such as is well known in the art; the material known in the art as "Neoprene" being admirably suited for my purpose.

35 The valves 15 and 16 are held in position by a cage or retainer 17 comprising an upper plate portion 18 centrally apertured at 19 and depending arcuate inwardly tapering portions 20 and 21 connected with opposite edges of the plate 40 portion 18 and spaced from the side wall of the casing 8, the adjacent upwardly extending edges of the members 20 and 21 being spaced apart as shown to provide diametrically opposed slots 22 and 23 extending lengthwise of the cage through- 45 out the greater portion of its length—in the construction shown, throughout the length of the cage and the length of the series of air inlets 13 and 14. Preferably the members forming the cage are made of sheet metal and may, if desired, 50 be formed of a single sheet thereof stamped or pressed into the desired shape.

The flap valves are supported at their upper marginal edges on the cage in registration with the arcuate members 20 and 21. The means 55 shown for so supporting the flap valves comprise pins 24 struck outwardly from the upper portions of the members 20 and 21 and which extend into openings 25 in the flap valves, whereby the flap valves depend from the cage and the portions 60 thereof opposing the air inlets 13 and 14 are movable crosswise of the device into and out of a position in which they close the air inlets.

The cage is so positioned in the casing 8 as to cause its arcuate members 20 and 21 and the 65 flap valves carried thereby to span the series of slots 13 and 14 in which position of the parts the slots 22 and 23 register with the solid portions of the side wall of the casing 8. The casing is supported in this position by means of substantially 70 diametrically opposed lugs 26 extending laterally from the marginal edge of the plate 18, these lugs seating on the lower end walls of short grooves 27 provided on the inner surface of the side wall of the casing 8 and extending length- 75 wise thereof.

The parts are so proportioned as shown that when the flap valves 15 and 16 are displaced from the air inlets 13 and 14 as shown in Figs. 2 and 4, the lower edges of the arcuate members 20 and 21 and the flap valves 15 and 16 are spaced from the casing 8 thus affording passages through which air drawn into the device through the inlets 13 and 14 may pass downwardly, without obstruction, into the casing 8 below the cage and thence to the engine cylinder; air also passing 10 from these air inlets through the slots 22 and 23 into the cage and discharging through its open bottom into the casing below the cage.

The upper end of the casing 8 is closed by a cap 28 hereinbefore referred to, screwed into the 15 casing 8 and having a centrally disposed air outlet 29 controlled by a ball check 30, the upper end of the cap being provided with a nipple 31 adapted for attachment to the end of a flexible 20 hose shown at 32. This cap opposes the plate portion 18 of the cage and prevents upward displacement thereof.

In the use of the device the casing 8 is screwed onto a spark-plug-receiving opening as above described. When the engine is operated the 25 piston in the cylinder to which the device is attached operates to draw air into the casing 8 through the openings 13 and 14 and expel it at high pressure through the opening 29 into the 30 hose 32.

The flap valves 15 and 16 being supported at 35 marginal portions as described are thus free to move at their portions opposing the air inlets 13 and 14 and without any interference between them and any frictional resistance, thus rendering them very sensitive in action. Furthermore, provision is afforded by the construction shown and described for the free, substantially unobstructed flow of the air from the air inlets 13 and 15 into the interior of the lower end of the casing 8 and in such volume as to prevent vacuum produced on the suction stroke of the piston of the pumping cylinder from becoming sufficiently effective on the gas intake of the engine as to draw gasoline into this cylinder.

40 In the particular construction shown the cage 17 not only serves as a support for the flap valves but also as a means for limiting inward movement of the free edge portions thereof on the suction stroke of the pumping cylinder, serving 45 to permit the flap valves to move inwardly sufficiently far for effecting the desired air flow through the device but preventing flapping or fluttering of the flap valves as would occur in case no such stops were provided and which 50 would manifestly be objectionable.

The sensitivity of the flap valves is effective 55 not only as a factor in developing a high degree of efficiency in the pumping of air, permitting high pressures to be developed, but also 60 as a factor in preventing the pumping of gasoline.

While I have illustrated and described a particular construction embodying my invention I do not wish to be understood as intending to 65 limit it thereto as the same may be variously modified and altered and the invention embodied in other forms of structure without departing from the spirit of the invention.

What I claim as new and desire to secure by 70 Letters Patent, is:

1. A device of the character described comprising a casing adapted for communication with the interior of a cylinder of an internal combustion engine, said casing having an air inlet in 75

its side wall, a valve cage in said casing and spaced therefrom, and a flap valve between said casing and cage and secured in place at its upper marginal portion and presenting a free depending portion extending generally lengthwise of the device and cooperating with said air inlet, said cage having a slot beyond said flap valve and extending generally in the direction of the length of the device and substantially throughout the length of said cage whereby a portion of the air drawn into said casing passes through said slot into said cage for discharge from an end thereof.

2. A device of the character described comprising a casing adapted for communication with the interior of a cylinder of an internal combustion engine, said casing having air inlets in its side wall, a valve cage in said casing and spaced therefrom, and flap valves between said casing and cage and secured in place at their upper marginal portions and presenting free depending portions extending generally lengthwise of the device and cooperating with said air inlets, said cage having a slot located beyond said flap valves and extending generally in the direction of the length of the device and substantially throughout the length of said cage whereby a portion of the air drawn into said casing passes from said slot into said cage for discharge through an end thereof.

3. A device of the character described comprising a casing adapted for communication with the interior of a cylinder of an internal combustion engine, said casing having air inlets in its side wall, a valve cage in said casing and spaced therefrom, and opposed flap valves between said casing and cage and secured in place at their upper marginal portions and presenting free depending portions extending generally lengthwise of the device and cooperating with said air inlets, said cage having slots located adjacent longitudinal edges of said flap valves and beyond said flap valves and extending generally in the direction of the length of the device and substantially throughout the length

of said cage, whereby a portion of the air drawn into said casing passes through said slots into said cage for discharge through an end thereof.

4. A device of the character described comprising a casing adapted for communication with the interior of a cylinder of an internal combustion engine, said casing having an air inlet in its side wall, a valve cage in said casing having an upper plate portion by which said cage is supported in said casing, the lower portion of said cage being spaced from the side wall of said casing, and a flap valve in said casing secured in place at its upper marginal portion and presenting a free depending portion extending generally lengthwise of the device and cooperating with said air inlet, said cage having a slot located beyond said flap valve and extending generally in the direction of the length of the device and substantially throughout the length of said cage, whereby a portion of the air drawn into said casing passes through said slot into said cage for discharge through an end thereof.

5. A device of the character described comprising a casing adapted for communication with the interior of a cylinder of an internal combustion engine, said casing having air inlets in its side wall, a valve cage in said casing comprising an upper plate portion at which said cage is supported in said casing and plate portions depending from said upper plate portion and spaced from the side wall of said casing, and flap valves between said depending plate portions and said casing and secured in place at their upper marginal portions and presenting free depending portions extending generally lengthwise of the device and cooperating with said air inlets, said plate portions being spaced apart at their adjacent edges to present slots located adjacent longitudinal edges of said flap valves and beyond said flap valves and extending generally in the direction of the length of the device and substantially throughout the length of said cage.
